UNITED STATES PATENT OFFICE.

EDWARD J. COVERT, OF BAY CITY, MICHIGAN.

DRINKING-CUP.

1,127,739.

Specification of Letters Patent.

Patented Feb. 9, 1915.

Application filed October 20, 1913. Serial No. 796,242.

To all whom it may concern:

Be it known that I, EDWARD J. COVERT, a citizen of the United States of America, residing at Bay City, in the county of Bay 5 and State of Michigan, have invented certain new and useful Improvements in Drinking-Cups; and I do hereby declare the following to be a full, clear, and exact description of the invention, such as will 10 enable others skilled in the art to which it appertains to make and use the same.

My invention relates to improvements in drinking cups, more especially in cups for fountains and its object is to provide a cup 15 adapted to be used in conjunction with the so-called "bubbler" drinking fountain, from which fountain water is discharged from an overflowing nozzle, and to provide a device that is easily and readily cleaned, 20 and that is compact and portable.

To drink from the ordinary bubbler fountain is inconvenient, because one is required to stoop over the same and bring the mouth close above the nozzle from which the water 25 escapes. This device is intended to receive the water from the nozzle and convey the same in a cup from which one may conveniently drink as occasion may require.

My invention consists essentially of a cup 30 from which to conveniently drink and provided with a conduit having a bottom opening to receive the water, and adapted to convey the same upward and into the cup, said conduit being adapted to be opened and 35 cleaned as occasion may require.

An embodiment of my invention is represented in the accompanying drawings, in which:—

Figure 1 is a plan view of the same; Fig. 40 2 a side view of the same; Fig. 3 a vertical section on the line 3—3 of Fig. 1; and Fig. 4 a perspective of the device, with the conduit opened.

Like numbers refer to like parts in all 45 of the figures.

1 represents a cup, preferably of metal and of any suitable size and shape, preferably as shown, and having a depression 2 in the rim thereof at one side to permit the 50 water to overflow from the conduit into the cup.

3 is a suitable handle on the cup for conveniently using the same.

4 is a hollow conduit extending from beneath the bottom of the cup to opposite the depression 2, the margins of this conduit being fitted closely to the outer surface of the cup. The upper end of the conduit is provided with an inwardly turned flange 5 to direct the water into the cup and the bottom of the conduit beneath the axis of the cup is provided with an inlet opening 6. When this device is placed above a "bubbler" nozzle 9, as illustrated in Fig. 3, the water will flow through the opening 6 and 65 upward in the conduit and thence inward over the depressed portion 2 of the margin, and thus the cup may be filled and used to drink therefrom. This conduit is preferably provided with an arm 7 pivoted at 8 70 to the outer end of the handle 3, whereby the conduit is supported in place in contact with the cup for use as described, and may be freely swung away from the cup whenever desirable for cleaning or any like purpose. 75

What I claim is:—

1. A drinking cup having an outside conduit attached thereto, said conduit having an opening beneath the cup adapted to receive water from a "bubbling" fountain, and a top opening to discharge water into the cup. 80

2. A drinking cup, having a depression in the rim, a conduit on the outside of the cup 85 having a bottom opening adapted to receive water from a "bubbling" fountain, and an inwardly turned flange above said depression to direct the water into the cup.

3. A drinking cup, and a conduit on the 90 outside of the cup pivoted to swing away from the same, said conduit having a bottom opening beneath the cup adapted to receive water, and an inwardly turned flange at the top to direct the water into the cup. 95

4. A drinking cup, and a conduit formed by a hollow member having its margin fitting the outside of the cup, said conduit being movable away from the cup and provided with an opening at the bottom, and 100 an inwardly turned flange at the top.

5. A drinking cup, having a depression

in the rim, a handle on the cup, a hollow conduit having its margin fitting close to the outside of the cup and extending beneath the same, an opening in the bottom of the conduit, an inwardly projecting flange on the same above the said depression, and an arm on the conduit pivoted to the handle.

Copies of this patent may be obtained for five cents each, by addressing the "Commissioner of Patents, Washington, D. C."

In testimony whereof I affix my signature in presence of two witnesses.

EDWARD J. COVERT.
